US00D873910S

(12) **United States Design Patent** (10) Patent No.: **US D873,910 S**
 Tsiopanos et al. (45) Date of Patent: ** Jan. 28, 2020

(54) **MEDIA PROCESSING DEVICE**

(71) Applicant: **ZEBRA TECHNOLOGIES CORPORATION**, Lincolnshire, IL (US)

(72) Inventors: **Konstantinos Tsiopanos**, Selden, NY (US); **Roy P. Lyman**, Coventry, RI (US); **Jorge Tomas**, Wrentham, MA (US)

(73) Assignee: **Zebra Technologies Corporation**, Lincolnshire, IL (US)

(**) Term: **15 Years**

(21) Appl. No.: **29/680,020**

(22) Filed: **Feb. 12, 2019**

Related U.S. Application Data

(63) Continuation of application No. 29/544,950, filed on Nov. 8, 2015, now Pat. No. Des. 844,699, which is a continuation-in-part of application No. 29/533,536, filed on Jul. 17, 2015, now Pat. No. Des. 829,812.

CLAIM

We claim the ornamental design for a media processing device, as shown and described.

DESCRIPTION

FIG. 1 is a perspective view of a media processing device according to our new design;

FIG. 2 is another perspective view thereof;

FIG. 3 is a top view thereof;

FIG. 4 is a bottom view thereof;

FIG. 5 is a first side view thereof;

FIG. 6 is a second side view thereof;

FIG. 7 is a back view thereof; and,

FIG. 8 is a front view thereof.

The broken lines are directed to environment and are for illustrative purposes only. The broken lines form no part of the claimed design.
